UNITED STATES PATENT OFFICE

HARRY E. HONIGBAUM, OF RICHMOND HILL, NEW YORK

COMPOSITION SHINGLE

Application filed April 27, 1928. Serial No. 695,000.

This invention is a composition shingle which may be constructed from any suitable material commonly used in the manufacture of shingles of this character and the invention is more especially an individual shingle in contradistinction to the well known strip shingles.

The accompanying drawing illustrates one practical embodiment of the invention, but the construction shown therein is to be understood as illustrative, only, and not as defining the limits of the invention.

Figure 1 is a perspective view of a shingle embodying the present invention; and,

Figure 2 shows six of such shingles laid in three courses.

The shingle of the present invention may be made of any suitable prepared roofing material, such for example as material having a felt base impregnated with pitch or asphaltum and having a ground slate finish. This material is tenacious, durable and economical and is well adapted for use in the making of composition shingles.

The shingles are blanked out from such material preferably in the form shown in Figure 1 wherein the shingle proper is shown as substantially rectangular in shape and is provided at one of its corners with two oppositely laterally projecting wings 1. These wings may be of any suitable size and shape, but their upper edges are preferably cut so as to slope toward the shingle proper as shown at 2.

The shingles are blanked out flat and are laid flat in successive courses after the manner shown in Figure 2. The lowermost course shown is designated A and after this course has been laid and nailed down by nails

3 at the two opposite corners of each shingle, the next course B is laid with the wings 1 of the shingles of such course introduced by heading the shingles of the course B upwardly under the edges of each two adjacent shingles of the first course and thereupon each shingle of the second course B is nailed down by nails 4 after which the third course C is laid and nailed down in like manner and subsequent courses follow in the same way.

It will be noted from Figure 2 that when

the shingles are laid in the manner described, successive courses do not have an appreciable overlap with respect to preceding courses and it has been found in practice that this fact makes it possible to cover a relatively large roof with an astonishingly small number of shingles constructed and laid in the manner described. This greatly economizes not only in the cost of material, but also in the cost of labor incident to the laying of such roof and without in anywise tending to produce a leaky assemblage. Moreover, when the shingles are in place upon the roof, the wings 1 are concealed from view and the optical effect is highly pleasing. Furthermore, inasmuch as the wings underlap shingles of preceding courses adjacent the point where the shingles of such courses are nailed, there is no tendency of the weather edges of the shingles to lift or curl and the wings cannot work loose, this being especially true when the upper edges of the wings are sloped as shown at 2, which causes them to interlock against removal.

It will be further noted from Figure 2 that the shingles are laid with one corner to the weather; that is to say, they are laid with their diagonal dimensions extending vertically and horizontally of the roof, in contradistinction to rectangular shingles which are laid with their edges disposed horizontally and vertically of the roof. Thus, when the shingles are assembled on a roof, they present, as shown in Figure 2, a substantially diamond shaped appearance, with only one corner of each shingle to the weather and the other three corners of each shingle covered by the shingles of superimposed courses.

The accompanying drawing shows the shingle in its preferred practical form, yet changes in shape of the shingle or wings can manifestly be made without departing from the spirit of the invention which is to be understood as commensurate with the appended claims.

I claim:

1. A flexible shingle of composition roofing material comprising a body having an overall rectangular contour, flat throughout its entire extent and adapted to be laid with

one corner to the weather and provided at the apex of said weather corner with wings extending laterally in opposite directions beyond the contiguous lateral converging edges 5 of said overall rectangular contour of the body, and lying in the same plane as the remainder of the shingle, said wings being of sufficient transverse length to extend in flat position beneath portions of the bodies of two 10 juxtaposed underlying shingles of the preceding shingle course to hold down the weather corner of the shingle.

2. A flexible shingle of composition roofing material comprising a body having an 15 overall rectangular contour, flat throughout its entire extent and adapted to be laid with one corner to the weather and provided at the apex of said weather corner with wings extending laterally in opposite directions beyond 20 the contiguous lateral converging edges of said overall rectangular contour of the body and lying in the same plane as the remainder of the shingle, with the upper edges of said wings sloping in a downward direction 25 toward the body of the shingle, said wings being of sufficient transverse length to extend in flat position beneath portions of the bodies of two juxtaposed underlying shingles of the preceding shingle course to hold down 30 the weather corner of the shingle.

3. A flexible shingle of composition roofing material comprising a square body proper having parallel opposite edges, and provided at the weather corner thereof with integral 35 upwardly hooked locking wings or tabs which extend laterally beyond the body proper, said body proper and wings or tabs being flat and all occupying a common plane.

4. A flexible shingle of composition roofing material comprising a body proper having parallel opposite edges, and provided at the weather corner thereof with integral upwardly and laterally projecting locking wings or tabs which extend laterally beyond 45 the body proper, said body proper and wings or tabs being flat and all occupying a common plane.

In testimony whereof I have signed the foregoing specification.
so HARRY H. HONIGBAUM.
